(57) CLAIM

The ornamental design for a golf putter head, as shown and described.

DESCRIPTION

FIG. 1 is a perspective view of the golf putter head according to my design;

FIG. 2 is a side elevational view of the golf putter head shown in FIG. 1;

FIG. 3 is a top elevational view of the golf putter head according to my design;

FIG. 4 is a front elevational view of the golf putter head according to my design; and,

FIG. 5 is a rear elevational view of the golf putter head according to my design.

The broken line showing of the fragmented shaft is for illustrative purposes only and forms no part of the claimed design.
